SIGVART JOHAN BENNETTER, OF OSLO, NORWAY

MEANS FOR COOLING PERISHABLE FOOD PRODUCTS

Application filed May 4, 1928. Serial No. 275,201.

The invention relates to cooling perishable goods such as meat, fish, fruit, ale and the like during their transport in railway cars and the object of the invention is preserving by cooling in a suitable manner such perishable loads.

It is well known that the transport of perishable goods has hitherto met with great difficulties especially when the goods have to be transported over long distances, as an example through hot and cold districts. Such difficulties are also increased by the fact that the temperature of the goods, in order to avoid destruction, should be maintained at a certain height and many goods are very sensitive to a rise of temperature if a development of bacteria and the like are to be prevented.

According to the present invention these difficulties are overcome in a quite satisfactory manner by very simple means by arranging a compelled circulation of the air of the car so that the heat contained in the goods to be cooled is removed during a short period so that the development of the bacteria is checked and the goods preserved in their natural state. In this way fresh killed meat may be transported without being pre-cooled in cooling rooms, whereby time and money are saved in addition to the fact that cooling rooms are not always available.

In stationary plants it is known to cool goods in a cooling chamber by circulating a current of air over a cooling material in a direction opposite to the direction of motion of the cooling material and then over the goods. The adoption of such a scheme to the present problem however has met with considerable difficulties which are further increased by the fact that fresh air cannot be admitted to a railway car as in a stationary plant and the circulation of air has to take place in closed cars.

In a known car for the said purpose the air is forced by a fan from the bottom part of the car through a cooling device at one end of the car and is passed in a longitudinal direction of the car to the opposite end thereof and thence recirculated through the bottom of the car and the cooling device. Such arrange-

ment however involves two serious disadvantages viz. the cooling air will not be uniformly distributed in the car room and a circulation will cease immediately the fan is stopped.

55

These disadvantages are avoided according to the present invention.

The invention consists therein that fresh air of uniform temperature is obtained in all parts of the car room by special circulating arrangement connected to a combined air cooling and cleaning arrangement.

According to the invention the air is gathered in special channels arranged around the upper part of the car room. From these channels the air is sucked in by a fan and is forced by the same through a washing vat at the upper part of the car room. From this vat the air is passed into a cleaning container in which it obtains an intimate contact with cooling means so as to be cooled and cleaned by the same and leaves the same through a series of holes at the upper part of the same and will pass downward along the cold outer sides of the container being thereby dried as the moisture will be kept back by the cold walls of the container so that the dried, cooled and cleaned air will be returned to the car room and will sink gradually through the same, whereupon the air after being heated by the goods will be gathered again in the gathering channels.

The invention will be clearly understood from the following description in which the nature of the invention is fully described. A suitable form of a car adapted for performing the invention is illustrated in the accompanying drawings in which:

Fig. 1 is a diagrammatic side view.

Fig. 2 is a sectional view upon a central cross-line looking toward the left part of the car shown in Fig. 1.

Fig. 3 is a plan view.

Fig. 4 is a central longitudinal section.

Fig. 5 is a sectional view of a car similar to Fig. 2 having the fan arranged in the interior of the car and driven by belt whereas the form according to Fig. 2 has the fan exterior of the car arranged to be driven by a flexible shaft.

95

100

Fig. 6 is a sectional view upon a horizontal line through the precooler and the main cooler.

5 A fan 1 which is driven from a wheel shaft by a flexible shaft or other suitable mechanism sucks air from the interior of the car through a channel 2 and forces the same through a channel 3 which communicates with a precooler and washer 4 which takes up
 10 cold water from the main cooler which communicates with the same through an opening near to the bottom. In the precooler the air passes along the surface of the cooling water and passes through a special drum 6 into
 15 the main cooler 5 (Fig. 4) surrounded by cooling means as ice or ice and salt. The drum is perforated at its lower part so that the air will pass from the same first downward and then pass upwards and leave the
 20 container 5 through apertures 7 at the upper part of the same. In this way the air will obtain a very intimate contact with the cooling means and therefore all impurities in the air will be kept back. From the apertures 7
 25 the air will pass downward along the outer sides of the container through channels 8. The channels have their opening in a longitudinal direction of the car and through this opening the cold air will sink downward
 30 owing to its low temperature. When passing the outer cold sides of the container the air will be dried simply by the condensation of a considerable portion of its contents of water. The cold air now will sink gradually
 35 to the bottom of the car and will thereupon, as it is gradually heated, pass upwards again along the walls of the car and will be sucked in through apertures 10 in the sides of the channels 11 communicating with the suction
 40 channel 2.

The water deposited in the channels 8 is removed by a drip channel 9. As the ice melts in the container 5 ice water will pass through the mentioned opening at the bottom
 45 into the precooler 4 so that this is maintained filled with cold water to a suitable degree. The precooler is provided with an opening through which water is removed in order to prevent overfilling.

50 When the fan is stopped it will be understood that the cooling action will not be interrupted. Owing to the cooling action of the walls of the ice container the air will still sink gradually toward the bottom and
 55 will pass upward along the walls in the same way as when the fan is acting. However the air will now owing to the fact that it is not sucked in through the apertures 10, continue to the upper part of the car, that is to say,
 60 to the upper part of the container 5 whereupon it is cooled again and will pass downward for further circulation.

In order that the temperature may be maintained unchanged in the car, a valve 12
 65 controlling the flow of air is placed in the

suction channel 2 and controlled by a thermostat 13 so that the valve 12 when the temperature is becoming lower than required is closed and when the temperature is becoming higher than required is automatically 70 opened. By such means a nearly uniform temperature is obtained, the variations being scarcely more than 1 to 2° centigrade. The thermostat excludes the risk of the temperature becoming so low that goods are 75 damaged by freezing. On the other hand it is possible to obtain an intensive cooling action so that heat in the goods may be removed during a short period and the goods quickly 80 cooled to the temperature required for safe transport.

In this matter it will be possible to transport the goods without any risk through districts having greatly varying temperatures as the thermostat will automatically 85 maintain a uniform temperature necessary for checking bacteria life.

In order to reduce the consumption of ice as much as possible, the inner walls of the car are preferably covered by or consist of polished metal or the like. The polished surface may be arranged as a covering surface of an insulating packing on the inside of the walls of the car.

It will be understood that the invention is 95 not limited to the details shown and described and that the same may be varied without departing from the scope of the invention as set forth in the following claims.

Having now particularly described and ascertained the nature of my said invention and in what manner the same is to be performed, I declare that what I claim is:

1. Apparatus for cooling perishable goods such as meat, fish, fruit and ale during transport in railway cars, comprising a compartment arranged longitudinally in the car and adapted to receive the goods, a container for cooling medium disposed longitudinally in the top part of the car compartment and presenting cooling surfaces forming the exterior container walls, outlets disposed in said walls, means for sucking air from the interior of the compartment and forcing it through the cooling medium within the container, and out through said outlets and means for directing such air past said cooling surfaces and in the form of a descending central stream of cold air substantially over the whole length of the compartment.

2. Apparatus for cooling perishable goods such as meat, fish, fruit and ale during transport in railway cars, comprising a compartment arranged longitudinally in the car and adapted to receive the goods, a container for cooling medium disposed longitudinally in the top part of the car compartment and presenting cooling surfaces forming the exterior container walls, outlets disposed in said walls in a longitudinal direction of the com-

- partment, a perforated drum arranged inside the container and the cooling medium therein, channels connecting the drum with the compartment, means for sucking air from the interior of the compartment through the channels into the drum and forcing it out through the perforations, through the cooling medium within the container and out through said outlets, and means for directing such air past said cooling surfaces and in the form of a descending central stream of cold air substantially over the whole length of the compartment.
3. Apparatus for cooling perishable goods such as meat, fish, fruit and ale during transport in railway cars, comprising a compartment arranged longitudinally in the car and adapted to receive the goods, a container for cooling medium disposed longitudinally in the top part of the car compartment and presenting cooling surfaces forming the exterior container walls, outlets disposed in said walls in a longitudinal direction of the compartment, a perforated drum arranged inside the container and the cooling medium therein, a precooling and washing device connected at one end with the drum, channels connecting the other end of said device with the compartment, means for sucking air from the interior of the compartment through the channels into the device and forcing it through the channels to and through the device and then into the drum and forcing it out through the perforations through the cooling medium within the container, and out through said outlets, and means for directing such air past said cooling surfaces and then in the form of a descending central stream of cold air substantially over the whole length of the compartment.
4. An apparatus as claimed in claim 1, in which the cooling surfaces constitute the bottom walls of the container and in which the means for directing the air past said cooling surfaces comprise channels communicating with the container and arranged along the side walls of the same in order to effect drying of the cooled air.
5. An apparatus as claimed in claim 1, in which the cooling surfaces constitute the bottom walls of the container and in which the means for directing the air past said cooling surfaces comprise channels communicating with the container and arranged along the side walls of the same in order to effect drying of the cooled air, said channels leading to a central longitudinal outlet slot for air having passed along the cooling surfaces and descending into the compartment.
6. An apparatus as claimed in claim 2, in which the means for circulating the air comprises a fan with a suction channel connected with the interior of the compartment and a delivering channel connected with the drum, said suction channel being provided with a closing valve controlled by a thermostat in such a manner that the latter opens the valve at its maximum temperature and closes the valve at its minimum temperature whereby the volume of the stream of air will depend upon the temperature of the compartment.
7. An apparatus as claimed in claim 1, in which the cooling surfaces constitute the bottom walls of the container and in which the means for directing the air past said cooling surfaces comprise channels communicating with the container and arranged along the side walls of the same in order to effect drying of the cooled air, and including a drip channel arranged under the container to receive and carry off water formed by condensation on the cooling surfaces.
8. Apparatus for cooling perishable goods such as meat, fish, fruit and ale during transport in railway cars comprising a compartment arranged longitudinally in the car and adapted to receive the goods, a container for cooling medium disposed longitudinally in the top part of the car compartment and presenting cooling surfaces forming the exterior container walls, outlets disposed in said walls in a longitudinal direction of the compartment, top channels arranged laterally in the compartment and opening to the latter and connected to the inlet of the container, means for sucking air from the interior of the compartment into said top channels and forcing it through the cooling medium within the container, and out through said outlets, means for directing such air past said cooling surfaces and then in the form of a descending central stream of cold air substantially over the whole length of the compartment, so that the air rising along the longitudinal sides of the compartment is collected by the said top channels.
9. Apparatus for cooling perishable goods such as meat, fish, fruit and ale during transport in railway cars, comprising a compartment arranged longitudinally in the car and adapted to receive the goods, a container for cooling medium disposed longitudinally in the top part of the car compartment and presenting cooling surfaces forming the exterior container walls, outlets disposed in said walls in a longitudinal direction of the compartment, top channels arranged laterally in the compartment and opening to the latter and connected to the inlet of the container, a fan inserted in the connection between the two channels and the container inlet for sucking air from the interior of the compartment into said top channels and forcing it through the cooling medium within the container, and out through said outlets, means for directing such air past said cooling surfaces and then in the form of a descending central stream of cold air substantially over the whole length of the compartment.

the compartment, so that the air rising along the longitudinal sides of the compartment is collected by the said top channels.

- 5 10. Apparatus for cooling perishable goods in a car, comprising a cooling device with cooling medium arranged longitudinally in the top of the car, a container arranged also in the top of the car and receiving cold 10 melting water from the cooling device, means for sucking air from the compartment of the car and for forcing such air over said melting water, means for thence conducting the air in contact with the cooling medium 15 to further cool and to purify same, and means for conducting the air so cooled back into the car compartment in the form of a descending central stream substantially over the whole length of the compartment.
- 20 In witness whereof I affix my signature.
